UNITED STATES PATENT OFFICE.

GEORGE R. FORD, OF ST. LOUIS, MISSOURI.

DESIGN FOR A MATCH.

SPECIFICATION forming part of Design No. 30,657, dated May 2, 1899.

Application filed April 6, 1899. Serial No. 712,026. Term of patent 14 years.

To all whom it may concern:

Be it known that I, GEORGE R. FORD, a citizen of the United States, residing at St. Louis, in the State of Missouri, have invented and produced a new and original Design for Matches, of which the following is a specification, reference being had to the accompanying drawings, forming part thereof.

Figure 1 is a perspective view of a match, showing my new design. Fig. 2 is a section on line 2 2 of Fig. 1.

As shown in the drawings, the leading or material feature of my design consists in the cylindrical formation of the body of the match, having a contracted cylindrical portion at one end and having at the other end a sphere. A rectangular depression is made in one side of the match-body, the base of which depression is flat. The end and side walls of the depression project at right angles to the base, the upper edges of the end walls being arc-shaped.

A is the body of the match, which at one end is formed spherical. The body A is cylindrical, and at the end opposite the sphere it is contracted and cylindrical, as shown at C. In the side of the body is a rectangular depression D, the base of which is flat. The walls E and F of the depression project at right angles to the base, the end walls E being bounded at their upper edges by arcs, as shown.

Having thus described my invention, what I claim as new, and desire to secure by Letters Patent, is—

The design for a match as herein shown and described.

GEORGE R. FORD.
